UNITED STATES PATENT OFFICE.

PHINEAS H. ADAMS, JR., AND ORSEMAS T. X. ADAMS, OF CHICAGO, ILLINOIS,
ASSIGNORS TO MELINDA PECK, OF SAME PLACE.

APPARATUS FOR USE IN DECOMPOSING METALLIC SALTS AND DESULPHURIZING ORES.

SPECIFICATION forming part of Letters Patent No. 399,112, dated March 5, 1889.

Application filed December 6, 1888. Serial No. 292,840. (No model.)

To all whom it may concern:

Be it known that we, PHINEAS H. ADAMS, Jr., and ORSEMAS T. X. ADAMS, citizens of the United States, residing at Chicago, Illinois, 5 have invented certain new and useful Improvements in Apparatus for Use in Decomposing Metallic Salts and Desulphurizing Ores, of which the following is a specification.

The object of our invention is to improve 10 an apparatus for mechanically decomposing chemical compounds, metallic salts, and desulphurizing ores or their resulting material, when the substances treated are in a molten condition, by the action of centrifugal force; 15 and our invention has more particular reference to the running-gear employed in such apparatus.

In the drawings, Figure 1 is a vertical section of the apparatus, showing the lower portion 20 of the running-gear in elevation. Fig. 2 is a plan view taken in the line 1 1 of Fig. 1, with a portion of the upper plate of the journal-box removed, and Fig. 3 is a plan view taken in the line 2 2 of Fig. 1.

25 In making our improved apparatus for decomposing chemical compounds, metallic salts, or salts of metal, and desulphurizing ores, we make a receiving-vessel, V, adapted to receive the substance to be treated when 30 in a molten condition. This receiving-vessel is mounted and rests upon an actuating-shaft, A, to which it is fixed or keyed in such a way that by the rotation of the shaft the receiving-vessel will be revolved. The receiving-vessel 35 may be made in such a way as will secure the required strength and reduce the conduction of heat from the interior to the exterior. It may be surrounded by a curbing and have a removable bottom to facilitate 40 the removal of the material which is not thrown off at the top by the action of centrifugal force, and in other respects it may be made as will be calculated to subserve the end in view and permit of its being rotated 45 at a high rate of speed for the separation of particles of different degrees of density in the matter treated. Many of these parts and the details of their construction, as they do not form the subject-matter of our present claims, 50 need not be more fully described, as they will

be sufficiently understood from an inspection of the drawings.

The actuating-shaft A, which serves to rotate the receiving-vessel, is preferably provided with a joint or coupling, B, to enable 55 its upper portion to have a sufficient lateral play to accommodate it to the vibration of the receiving-vessel when rotating at a high speed. The lower portion of the actuating-shaft passes down through journal-boxes C C', 60 and preferably enters a step, C'', which serves to maintain the lower end in its proper vertical position. This bearing, however, may be dispensed with, if desired, as it does not sustain the weight of the actuating-shaft and its 65 superimposed load, although we prefer to use it as a convenient means of maintaining the lower end portion of the actuating-shaft in proper alignment.

The journal-boxes C C' are preferably composed of three horizontal disks, c, held a proper distance apart by rings D interposed between them, as shown in Fig. 1. Between these horizontal disks are arranged a number of wheels or rollers, d, whose axes are journaled 70 in the disks c in such position that their inner edges will bear against the actuating-shaft A, as shown in Fig. 2. In this way the actuating-shaft is composed of two parts—a flexible or laterally-vibratable upper portion 75 and a rigidly-journalized lower portion. To assist in supporting the flexible upper portion of the shaft in its proper vertical position, a laterally-yieldable journal or box, x, may be employed, as shown in Fig. 1. 85

As the actuating-shaft is rotated, it will cause the wheels or rollers d to rotate with it, and thus greatly reduces and obviates the lateral friction between the vertical portion of the actuating-shaft which passes through the 90 journal-boxes, intended to preserve it in its vertical position, and so prevent extreme or injurious lateral friction. The importance of thus reducing and obviating lateral friction between the actuating-shaft and the journal-boxes holding it in an upright position will be readily perceived when it is understood that the actuating-shaft is intended to support 95 and to rotate at a great speed the receiving-vessel when containing a heavy load of molten 100

material being treated. The lateral strain of a belt rotating a shaft thus arranged and operating must necessarily be very great. Without means to prevent great friction between the actuating-shaft and the journal-boxes C C' the difficulty of rotating the shaft and preventing it from becoming overheated would be such as to greatly impair the operativeness and practical character of the apparatus. It is obvious that changes could be made in the construction of these journal-boxes, and that mere rollers could be substituted for the wheels d , or the arrangement of the wheels themselves modified, and we do not therefore desire to confine ourselves strictly to the details of construction shown in the drawings and described above.

In order to support the weight of the actuating-shaft and its superimposed load, we prefer to arrange a frame, E, beneath the journal-box C', and to arrange two or more vertical wheels, F, journaled and supported in horizontal bearings in or attached to the frame, as shown in Fig. 1. Immediately above these vertical wheels F is arranged a horizontal disk or wheel, G, rigidly secured to and rotating with the actuating-shaft. The under surface of this wheel or disk is intended in operation to rest on the upper edges or peripheries of the wheels F, and as the disk G rotates with the actuating-shaft the wheels F will be caused to rotate, and thus decrease the amount of friction induced between the actuating-shaft and the bearing which sustains its weight. To still further divide and reduce this friction and assist in supporting the actuating-shaft, another set of vertical wheels, H, may be arranged lower down. A disk or wheel, I, is arranged on the actuating-shaft immediately above the wheels H, and keyed to it, so as to rotate with it. We prefer, however, to permit the disk I to be movable up and down the shaft while rotating with it, and to arrange a stop or collar, J, a little farther up the shaft, between which and the disk or wheel I a powerful spring of coiled wire, rubber, or other elastic material is interposed. This spring is intended to be of sufficient strength to support about half of the weight of the actuating-shaft and its superimposed load when the apparatus is in operation, and thus divide the weight resting upon the wheels F and H.

Of course it will be understood that the wheels H rotate with the rotation of the shaft, as above explained with reference to the wheels F. Around the bearing we prefer to arrange a box, K, inclosing the running-gear below the journal-box C', and fill this box more or less with a lubricant to insure a constant and perfect lubrication of the running-gear inclosed therein.

A power-shaft, L, provided with a pulley or belt-surface, l, rotated by the power of the works, is connected by a belt to a pulley or belt-surface, l', on the actuating-shaft to afford means for the rotation of the actuating-shaft and the parts connected therewith. This

pulley or belt-surface on the actuating-shaft is preferably arranged between the journal-boxes C and C', as shown in Fig. 1.

We have described a bearing containing two sets of vertical wheels for sustaining and dividing the weight of the actuating-shaft and its superimposed load, and in the claims we shall, for convenience, speak of two sets; but it is obvious that more than two sets of vertical wheels could be employed. When, therefore, we speak in the claim of "two sets" we desire it understood that by the use of these words we mean to include any number of sets more than one, and when we speak of a second set we mean to indicate any set of wheels below the top set.

What we regard as new, and desire to secure by Letters Patent, is—

1. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, a divided bearing for supporting the actuating-shaft and its superimposed load, comprising two sets of vertical wheels arranged in suitable bearings, and two horizontal disks arranged on the actuating-shaft and rotating as it revolves, and resting upon the upper peripheries of the vertical wheels and rotating them, and means for rotating the actuating-shaft, substantially as described.

2. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, a divided bearing for supporting the actuating-shaft and its superimposed load, comprising two sets of vertical wheels arranged in suitable bearings, and two horizontal disks arranged on the actuating-shaft and rotating as it revolves, and resting upon the upper peripheries of the vertical wheels and rotating them, a spring arranged on the actuating-shaft above the second disk, with its upper end against a collar or stop, and the second disk movable vertically, and means for rotating the actuating-shaft, substantially as described.

3. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, one or more journal-boxes maintaining the actuating-shaft in a vertical position, containing wheels or rollers which bear against the surface of the actuating-shaft and rotate with it, a divided bearing for supporting the actuating-shaft and its superimposed load, comprising two sets of vertical wheels arranged in suitable bearings and two horizontal disks arranged on the actuating-shaft and

rotating as it revolves, and resting upon the upper peripheries of the vertical wheels and rotating them, a spring arranged on the actuating-shaft above the second disk, with its upper end against a collar or stop, and the second disk movable vertically, and means for rotating the actuating-shaft, substantially as described.

4. In an apparatus for decomposing metallic salts or salts of metals and desulphurizing ores when in a molten state, the combination of a revoluble receiving-vessel adapted to receive molten material to be treated, a revoluble actuating-shaft rotating said vessel as it revolves, and comprising a flexible or laterally-vibratable upper portion and a rigidly-journaled lower portion, a laterally-yieldable journal for maintaining a flexible or laterally-vibratable upper portion of the actuating-shaft in a vertical position, one or more journal-boxes for maintaining the rigidly-journaled

lower portion of the actuating-shaft in a vertical position, containing wheels or rollers which bear against the surface of the actuating-shaft and rotate with it, a divided bearing for supporting the actuating-shaft and its superimposed load, comprising two sets of vertical wheels arranged in suitable bearings, and two horizontal disks arranged on the actuating-shaft and rotating as it revolves, and resting upon the upper peripheries of the vertical wheels and rotating them, a spring arranged on the actuating-shaft above the second disk, with its upper end against a collar or stop, and the second disk movable vertically, and means for rotating the actuating-shaft, substantially as described.
